DISPENSING CLOSURE FOR PRESSURIZED CONTAINERS

James K. Huling, Belleville, Ill., assignor to The Clayton Corporation of Delaware, St. Louis, Mo., a corporation of Delaware

Filed Mar. 22, 1963, Ser. No. 74,090

Term of patent 14 years

(Cl. D58—26)

FIG. 1.

FIG. 3.

FIG. 5.

FIG. 2.

FIG. 4.

FIGURE 1 is a perspective view of a dispensing closure for pressurized containers, embodying my new design. FIGURE 2 is a side elevational view thereof.

FIGURE 3 is a top plan view thereof.

FIGURE 4 is a front elevational view thereof.

FIGURE 5 is a rear elevational view thereof.

I claim:

The ornamental design for a dispensing closure for pressurized containers, substantially as shown.
